United States Patent Office

Des. 179,231

Patented Nov. 13, 1956

179,231

PAVING TILE

Marco Zanuso and Alberto Scarzella, Milan, Italy

Application January 3, 1955, Serial No. 33,785

Term of patent 7 years

(Cl. D18—2)

Fig. 1 is a plan view of a paving tile showing our new design, and

Fig. 2 is an edge view of our paving tile taken from the right side of Fig. 1.

We claim:

The ornamental design for a paving tile, as shown.

References Cited in the file of this patent

UNITED STATES PATENTS

D. 30,072 Thomas ----- Jan. 24, 1899